UNITED STATES PATENT OFFICE

152,678

DESIGN FOR A ROTARY POWER HANDSAW

Francis D. Dolan, Toledo, and Louis Vavrik, Rossford, Ohio, assignors to The American Floor Surfacing Machine Company, Toledo, Ohio, a corporation of Ohio

Application May 28, 1947, Serial No. 139,320

Term of patent 14 years

(Cl. D93—3)

To all whom it may concern:

Be it known that we, Francis D. Dolan and Louis Vavrik, both citizens of the United States, and residents of Toledo, in the county of Lucas and State of Ohio, and Rossford, in the county of Wood and State of Ohio, respectively, have invented a new, original, and ornamental Design for a Rotary Power Handsaw, of which the following is a specification, reference being had to the accompanying drawing, forming a part thereof.

In the drawing, Fig. 1 is a front perspective view of a rotary power handsaw, showing our new design; Fig. 2 is a front end view thereof; Fig. 3 is a top view thereof; Fig. 4 is a side view thereof of the side opposed to that shown in Fig. 1, and Fig. 5 is a rear end view thereof.

The dominant features of our design are shown in full lines.

We claim:

The ornamental design for a rotary power handsaw, substantially as shown and described.

FRANCIS D. DOLAN.
LOUIS VAVRIK.
